UNITED STATES PATENT OFFICE.

FAWCETT PLUMB, OF STREATOR, ILLINOIS.

KILN FOR BURNING BRICKS, TILES, &c.

SPECIFICATION forming part of Letters Patent No. 316,397, dated April 21, 1885.

Application filed January 8, 1885. (No model.)

To all whom it may concern:

Be it known that I, FAWCETT PLUMB, of Streator, in the county of La Salle and State of Illinois, have invented certain new and useful 5 Improvements in Kilns; and I do hereby declare the following to be a full, clear, and exact description of the invention, such as will enable others skilled in the art to which it app pertains to make and use the same.

10 My invention relates to an improvement in kilns for burning bricks, tiles, &c., the object of the invention being to provide improved means for supplying coal to the combustion-chambers of kilns; and with this end in view 15 my invention consists in certain features of construction and combinations of parts, as will be hereinafter described, and pointed out in the claim.

In the accompanying drawings, Figure 1 is 20 a view in elevation of a kiln provided with my improvement, and Fig. 2 is a view in vertical section of a portion of the kiln.

A represents a kiln of any approved construction, having an enlarged base, B, the upper portion of which forms an annular ledge, C, encircling the kiln.

Within the ledge C, at any desired distance apart, are inserted the fuel-hoppers D, which are preferably made of cast-iron, with outwardly-flaring sides *a*. The under side of each hopper is provided with a bottom flange, *b*, on which rests the upper ends of the inclined grate-bars *c*, the lower ends of which rest upon a cross-bar, *d*, secured at its ends in the brick-work. I may employ any improved construction of grate-bars, which may be stationary, or be provided with means for shaking and slicing the fuel for the removal of ashes and clinkers therefrom.

40 Within the kiln are constructed the flues E, which are located in front of the grate-bars and supported on the bottom F of the kiln.

Between the outer edge, *e*, of the bottom of the kiln and the lower end of the inclined 45 grate-surface is an opening, *f*, through which the clinkers and ashes fall into the ash-pit *g*.

Fresh air is admitted through the openings *h h* above the ledge, and conducted through the passages *i i*, which may be made of any 50 desired length, within the wall of the kiln, and admitted to the upper end of the flue E, each one of the flues being furnished with an air-

supply of this character and construction. The air is heated in its passage through the heated wall of the kiln, and is then discharged 55 into and commingled with the gases flowing upwardly through the flue, thereby insuring a complete combustion of the gases before they escape into the interior of the kiln; also, air may be conveyed through pipes G, located in 60 the ash-pits and extending upwardly into the flues E. This arrangement of pipes insures a constant supply of heated air to the unconsumed gases and products of combustion.

In the operation of the kiln the several hoppers are filled with coal, which drops through the openings H in the bottom of the hoppers and accumulates on the inclined grate-bars, forming a bed of fuel thereon. As the coal is consumed fresh coal will descend by its gravity, and thereby replenish the bed of fuel on the grate without necessitating the admission of outside air, as in the ordinary construction of kilns, which tends to materially deaden the fire, and hence cause a great loss of heat. The 75 ashes and clinkers are removed from time to time through the opening *f* and dropped into the ash-pit. As the coal is ignited it burns from the bottom of the magazine, and is first converted into gas and coke. The gases escape 80 inwardly and then upwardly through the flues E, fresh air being commingled therewith in the flues to supply the necessary quantity of oxygen to insure complete combustion of the gases before they enter the kiln.

85 A kiln thus constructed is, in effect, a base-burning kiln, it being operated on the principle of a base-burning furnace or heater.

Any number of hoppers may be located around the exterior of the kiln and supply heat 90 to the interior thereof for baking tiling I or any other articles.

In view of the fact that the arrangement of hoppers and inclined grate-surfaces renders the feed automatic or self-regulating, the labor of an attendant will be much less than is required to operate kilns as ordinarily constructed, and also a less amount of fuel will be required.

100 As it is evident that many changes in the construction and arrangement of parts might be resorted to without departing from the spirit of my invention, I would have it understood that I do not restrict myself to the ex-

act construction and arrangement of parts shown and described; but,

Having fully described my invention, what I claim as new, and desire to secure by Letters 5 Patent, is—

The combination, with a kiln having an enlarged base, of the vertical flues, the fire-boxes communicating with the vertical flues, the air-pipes entering the vertical flues below the fire-boxes, and the air-flues located outside of the

fire-boxes and communicating with the vertical flues above the fire-boxes.

In testimony whereof I have signed this specification in the presence of two subscribing witnesses.

FAWCETT PLUMB.
